LIQUID DISPENSER

Neil S. Waterman, Tarrytown, N. Y.

Application September 29, 1949, Serial No. 118,486

6 Claims. (Cl. 222—517)

1

This invention relates to new and useful improvements in liquid dispensers.

This invention proposes the construction of a new liquid dispenser which lends itself to be constructed from several simple rigid type plastic material parts, except for one leaf spring, and which is adapted to receive a bottle of liquid in an inverted condition and to dispense this liquid as desired.

More particularly, it is proposed to characterize the new liquid dispenser by the fact that it includes an open top container having downwardly and inwardly sloping sides forming a small well portion for the liquid at the bottom. It is proposed that this container be provided with means by which it may easily be mounted upon a wall or other object. Said open top container is provided with means for supporting an inverted bottle of liquid in position with the neck of the bottle positioned a short distance above said well portion so as to keep the well supplied with the liquid as long as the bottle contains any of the liquid.

Still further it is proposed that said open top container be provided with a small aperture in one of the sloping sides located in said well portion for the discharge of the liquid. A new and novel operator arm is mounted in a certain way within said open top container and is provided with a valve controlling said aperture. The leaf spring engages the back of this arm for urging the valve into its closed position. The open top container is also provided with a cover so that the inverted bottle may be fully encased.

Another object of the invention is the construction of a liquid dispenser as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a front view of a liquid dispenser constructed in accordance with this invention.

Fig. 2 is a side elevational view of Fig. 1.

Fig. 3 is a fragmentary enlarged vertical sectional view taken on the line 3—3 of Fig. 1.

Fig. 4 is a horizontal sectional view taken on the line 4—4 of Fig. 3.

Fig. 5 is a fragmentary vertical sectional view taken on the line 5—5 of Fig. 3.

2

Fig. 6 is a fragmentary horizontal sectional view taken on the line 6—6 of Fig. 5.

Fig. 7 is a front view of the arm with the valve which is used in the liquid dispenser.

Fig. 8 is a fragmentary perspective view of the top portion of the leaf spring which is used in the liquid dispenser.

The liquid dispenser, in accordance with this invention, includes an open top container 10 preferably constructed of rigid type plastic material and having downwardly and inwardly sloping sides 11 forming a small well portion 12 for liquid at the bottom of the container 10. Said container 10 is provided with means for supporting an inverted bottle of liquid with its neck positioned a short distance above said well portion 12. This means comprises a pair of vertically directed horizontally spaced lug portions 14. These lug portions are of T-shape in plan view (see particularly Fig. 4). The dot and dash lines 15 in Fig. 3 schematically indicate the neck portion of a bottle and illustrate the manner in which the bottle is supported in an inverted position upon the lugs 14. The well 12 is illustrated as filled with liquid up to the bottom edge of the neck of the bottle.

One of the sloping sides 11 has a small aperture 16 located in said well portion 12 for the discharge of said liquid. A short distance above this aperture 16 there is an opening 17 located above the well portion 12. A pair of horizontally spaced vertical tracks 19 (see Figs. 5 and 6) extend upwards along the sides of the opening 17 and terminate at the top edge of the container 10. An operator arm 20 is pivotally mounted on the bottom ends of the tracks 19, and extends downwards and is provided with a "press" projection 21 engaging through said opening 17. This arm 20 is also provided with a valve 22 engaging into said aperture 16 for closing said aperture from passage of said liquid. A leaf spring 24 having an enlarged top portion 25 is firmly mounted upon said tracks 19 and extends downwards against said arm 20 for holding said valve 22 closed.

The tracks 19 include a pair of horizontally spaced vertical flanges 26, and ribs 27 on the inner faces of said flanges 26 spaced slightly from the inner face of said sloping side 11 to form grooves 28 for receiving and holding said enlarged top portion 25 of the leaf spring 24. The ribs 27 have their faces 29 which are adjacent said sloping side 11, inclined (see Fig. 3) in order that said grooves 28 narrow towards their bottoms for firmly clamping said enlarged top por-

tion 25 of said leaf spring 25 in position. The leaf spring 24 has a pressed out rib 30 extending completely along its length for stiffening and reinforcing it. The enlarged top portion 25 is slightly separated from the remaining portion 5 of the leaf spring 24 with slits 31 in order to facilitate bending of the enlarged top portion 25 into position.

When the enlarged top portion 25 of the leaf spring 24 is slipped downwards into the grooves 28 it will become jammed against the inner face of the sloping side 11, while the leaf spring 24 extends downwards and in an inclined direction along the length of the arm 20. The arm 20 is formed with a top trunnion 33 which engages the bottom of the grooves 28 and by which said arm 20 is pivotally mounted on the bottom ends of the tracks 19. The arm 20 may pivot 10 inwards and outwards, using the trunnion 33 as a pivot. The inner face of the arm 20 is formed with a recess 34 extending its complete length into which the spring 24 engages so as to be firmly connected with the arm.

The projecting portion 21 of the arm 20 is imprinted with the word "press" (see Fig. 1), for indicating that the user should press this portion inwards. The valve 22 and the aperture 16 are of frusto-conical shape for eliminating possible leakage. The container 10 is also provided with a cover 36 adapted to cover the top portion of the inverted bottle within the dispenser. The cover 36 and the container 10 have the inner faces of their walls formed with vertically extending ribs 37 (see particularly Fig. 5). These ribs 37 act as guides for the sides of said bottle. The cover 36 is provided at its front and back with downwardly projecting lugs 38 and 39. The lug 38 engages in the top portions of the grooves 28, while the lug 39 engages in a recess 40 formed 25 inwards from the top of the container 10.

The top portion 25 of the spring 24 is jammed into position in the grooves 28 and serves to engage the top edge portion of the arm 20 for locking the arm 20 in position so that it is merely free to pivot upon the trunnion 33, but is limited 30 from moving upwards on the tracks 19. The container 10 is provided with means by which it may be attached to a wall. This means is in the form of an enlarged back portion 42 formed with a vertical groove 43 adapted to receive a complementary wall plate 44 which may be attached to a wall with screws 45. This wall plate 44 and groove 43 have sloping sides 46 (see Fig. 1). These sloping sides 46 are beveled, indicated by the double sloping sides 46 in Fig. 1. With this construction the wall plate 44 may be attached to a wall and the container 10 may be engaged on the wall plate by merely slipping it downwards so that the wall plate 44 engages the groove 43. The narrow end of the wall plate 44 and the groove 43, is at the top.

The operation of the device may be understood from the following:

The cover 36 may be removed and a bottle of liquid to be dispensed may be turned up side down and quickly placed in position on the tops of the lugs 14 so that liquid from the bottle fills the well 12. The "press" projection 21 may be pressed inwards to pivot the arm 20 inwards so as to open the aperture 16 to permit a suitable quantity of liquid to drip or flow out, as desired. The cover 36, the arm 20, and the wall plate 24 are also preferably made of rigid type plastic material.

An important feature of the invention resides in the construction of the tracks 19 and the manner in which the arm 20 and the leaf spring 24 are associated with said tracks for holding the valve 22 in its closed position. The particular construction shown is one in which the parts are simple and may be easily manufactured and assembled.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. In a liquid dispenser, an open top container having downwardly and inwardly sloping sides forming a small well portion for liquid at the bottom, means for supporting an inverted bottle of liquid in said container with the neck of said bottle positioned a short distance above said well portion, one of said sloping sides having a small aperture in said well portion for the discharge of said liquid and also having an opening above said well portion, tracks on said last mentioned sloping side positioned above said opening and extending upwards, an arm hanging a top trunnion pivotally mounted upon the bottom ends of said tracks, said arm extending downwards and having a "press" projection engaging through said opening and also having a valve engaging into said aperture for closing said aperture to the passage of said liquid, and a leaf spring extending downwards against said arm for holding said valve closed, said leaf spring having an enlarged top portion firmly mounted in said tracks by which said leaf spring is supported and said enlarged top portion of the leaf spring engaging above said top trunnion for holding said arm from moving upwards.

2. In a liquid dispenser, an open top container having downwardly and inwardly sloping sides forming a small well portion for liquid at the bottom, means for supporting an inverted bottle of liquid in said container with the neck of said bottle positioned a short distance above said well portion, one of said sloping sides having a small aperture in said well portion for the discharge of said liquid and also having an opening above said well portion, tracks on said last mentioned sloping side positioned above said opening and extending upwards, an arm having a top trunnion pivotally mounted upon the bottom ends of said tracks, said arm extending downwards and having a "press" projection engaging through said opening and also having a valve engaging into said aperture for closing said aperture to the passage of said liquid, and a leaf spring extending downwards against said arm for holding said valve closed, said leaf spring having an enlarged top portion firmly mounted in said tracks by which said leaf spring is supported and said enlarged top portion of the leaf spring engaging above said top trunnion for holding said arm from moving upwards, 50 said tracks comprising a pair of horizontally spaced vertical flanges, and ribs on the inner faces of said flanges spaced slightly from the inner face of said sloping side to form grooves for receiving and holding said enlarged top portion of said leaf spring.

3. In a liquid dispenser, an open top container

having downwardly and inwardly sloping sides forming a small well portion for liquid at the bottom, means for supporting an inverted bottle of liquid in said container with the neck of said bottle positioned a short distance above said well portion, one of said sloping sides having a small aperture in said well portion for the discharge of said liquid and also having an opening above said well portion, tracks on said last mentioned sloping side positioned above said opening and extending upwards, an arm having a top trunnion pivotally mounted upon the bottom ends of said tracks, said arm extending downwards and having a "press" projection engaging through said opening and also having a valve engaging into said aperture for closing said aperture to the passage of said liquid, and a leaf spring extending downwards against said arm for holding said valve closed, said leaf spring having an enlarged top portion firmly mounted in said tracks by which said leaf spring is supported and said enlarged top portion of the leaf spring engaging above said top trunnion for holding said arm from moving upwards, said tracks comprising a pair of horizontally spaced vertical flanges, and ribs on the inner faces of said flanges spaced slightly from the inner face of said sloping side to form grooves for receiving and holding said enlarged top portion of said leaf spring, said ribs having their faces adjacent said sloping side inclined in order that said grooves narrow towards their bottoms for firmly clamping said enlarged top portion of said leaf spring in position.

4. In a liquid dispenser, an open top container having downwardly and inwardly sloping sides forming a small well portion for liquid at the bottom, means for supporting an inverted bottle of liquid in said container with the neck of said bottle positioned a short distance above said well portion, one of said sloping sides having a small aperture in said well portion for the discharge of said liquid and also having an opening above said well portion, tracks on said last mentioned sloping side positioned above said opening and extending upwards, an arm having a top trunnion pivotally mounted upon the bottom ends of said tracks, said arm extending downwards and having a "press" projection engaging through said opening and also having a valve engaging into said aperture for closing said aperture to the passage of said liquid, and a leaf spring extending downwards against said arm for holding said valve closed, said leaf spring having an enlarged top portion firmly mounted in said tracks by which said leaf spring is supported and said enlarged top portion of the leaf spring engaging above said top trunnion for holding said arm from moving upwards, said tracks comprising a pair of horizontally spaced vertical flanges, and ribs on the inner faces of said flanges spaced slightly from the inner face of said sloping side to form grooves for receiving and holding said enlarged top portion of said leaf spring, said ribs having their faces adjacent said sloping side inclined in order that said grooves narrow towards their bottoms for firmly clamping said enlarged top portion of said leaf spring in position, said enlarged top portion of said leaf spring being slightly separated from said leaf spring with slits in order to facilitate bending of said enlarged top portion into said position.

5. In a liquid dispenser, an open top container having downwardly and inwardly sloping sides forming a small well portion for liquid at the bottom, means for supporting an inverted bottle of liquid in said container with the neck of said bottle positioned a short distance above said well portion, one of said sloping sides having a small aperture in said well portion for the discharge of said liquid and also having an opening above said well portion, tracks on said last mentioned sloping side positioned above said opening and extending upwards, an arm having a top trunnion pivotally mounted upon the bottom ends of said tracks, said arm extending downwards and having a "press" projection engaging through said opening and also having a valve engaging into said aperture for closing said aperture to the passage of said liquid, and a leaf spring extending downwards against said arm for holding said valve closed, said leaf spring having an enlarged top portion firmly mounted in said tracks by which said leaf spring is supported and said enlarged top portion of the leaf spring engaging above said top trunnion for holding said arm from moving upwards, said tracks comprising a pair of horizontally spaced vertical flanges, and ribs on the inner faces of said flanges spaced slightly from the inner face of said sloping side to form grooves for receiving and holding said enlarged top portion of said leaf spring, said top trunnion engaging the bottoms of said grooves by which said arm is pivotally mounted upon the bottom ends of said tracks.
6. In a liquid dispenser, an open top container having downwardly and inwardly sloping sides forming a small well portion for liquid at the bottom, means for supporting an inverted bottle of liquid in said container with the neck of said bottle positioned a short distance above said well portion, one of said sloping sides having a small aperture in said well portion for the discharge of said liquid and also having an opening above said well portion, tracks on said last mentioned sloping side positioned above said opening and extending upwards, an arm having a top trunnion pivotally mounted upon the bottom ends of said tracks, said arm extending downwards and having a "press" projection engaging through said opening and also having a valve engaging into said aperture for closing said aperture to the passage of said liquid, and a leaf spring extending downwards against said arm for holding said valve closed, said leaf spring having an enlarged top portion firmly mounted in said tracks by which said leaf spring is supported and said enlarged top portion of the leaf spring engaging above said top trunnion for holding said arm from moving upwards, one face of said arm being recessed, and said spring engaging in said recessed face.
